UNITED STATES PATENT OFFICE.

EUGENE IRVING HANSON, OF NEW ROCHELLE, NEW YORK, ASSIGNOR TO H. R. MALLINSON & CO., A FIRM COMPOSED OF HIRAM ROYAL MALLINSON AND E. IRVING HANSON, OF NEW YORK, N. Y.

DESIGN FOR A TEXTILE FABRIC.

50,384.

Specification for Design.

Patented Feb. 27, 1917.

Application filed September 23, 1916. Serial No. 121,883. Term of patent 3½ years.

To all whom it may concern:

Be it known that I, EUGENE IRVING HANSON, a citizen of the United States of America, and a resident of New Rochelle, in the county of Westchester, State of New York, have invented a new, original, and ornamental Design for a Textile Fabric, of which the following is a specification, reference being had to the accompanying drawing, showing my design.

The drawing shows a face view of a portion of fabric bearing my design.

In the drawing *a* indicates a black disk, *b* a green triangle, *c* a green rectangle, *d* an orange segment with a portion thereof broken off along straight lines, said figures *a*, *b*, *c* and *d* being so arranged relatively

to each other as to give the appearance of being superimposed, the whole being produced upon a white background *e*.

The color, arrangement and form of my design may be varied without departing from my invention, the essence of which resides in the appearance, upon a contrasting background, of superimposed simple geometrical figures of contrasting colors, substantially as shown and described.

The design is intended to be repeated on the fabric.

I claim:—

The design for a textile fabric substantially as shown and described.

E. IRVING HANSON.
